UNITED STATES PATENT OFFICE

GLEN C. CARNAHAN, OF CHICAGO, ILLINOIS, ASSIGNOR TO JAMES B. CLOW & SONS,
OF CHICAGO, ILLINOIS, A CORPORATION OF ILLINOIS

GAS-FIRED RADIATOR

Application filed June 13, 1928. Serial No. 235,125.

This invention pertains to radiator construction and more particularly to the construction of radiators and their loops of the direct fired type, that is, a radiator adapted 5 to be used as a heating unit independently of or in connection with the ordinary steam or water heating system in which the boiler is at a place remote from the radiator. Radiators of the character to which the invention pertains are ordinarily gas fired, but other fuels may be utilized for their operation.

Radiators of the character specified are ordinarily provided with a more or less enclosed combustion chamber beneath the bottom header, the individual loops being so constructed that when they are assembled a combustion chamber of desired length is provided. The space or spaces between adjacent loops is or are preferably closed about the margins of the chamber except across the top or a portion of the top which leaves an opening for the products of combustion to pass from the combustion chamber proper upwardly between the loops around the bottom header connection boss, if such is provided, and from thence upwardly along and between the one or more columns of adjacent loops. Sometimes a flue is provided for carrying off the products of combustion, as is illustrated in Daily Patent No. 1,580,651, dated April 13, 1926, but in other cases the products of combustion are permitted free and unlimited contact with the various columns of each loop and then pass directly into the room or into an area immediately above the radiator.

The bottom header of such radiators provides a boiler and storage reservoir for the water which is turned into steam and passes upwardly through the several columns of the loops and condenses on the walls thereof or in the top header and returns to the bottom header where the cycle may be continued. When the gases and other products of combustion have free and intimate contact with the entire area of the columns and the top header, or a large portion of such area, condensation of the steam within the columns and the top header is min-

imized and the heating efficiency materially lowered. The reasons for this are obvious for the rising heated gases and other products of combustion maintain the columns and top header walls at a high temperature 55 and prevent cold air from contacting with the condensing surfaces to the extent necessary for efficient and desirable operation of the radiator.

One of the primary objects of the invention, therefore, is to provide an arrangement whereby the gases and other products of combustion rising from the combustion chamber may be carried to the top of the radiator with as little contact with the columns and other condensing surfaces of each loop past which the products of combustion rise, as is possible.

Another object is to provide an arrangement which will induce a maximum contact 70 of cold air with the condensing surfaces and thereby cause greater condensation and higher heating efficiency. In this connection arrangement is made whereby proper draft from and through the combustion chamber is maintained.

Another object is to provide a construction which may be cheaply and economically manufactured as an individual part 80 of each loop casting in which it is desired to incorporate it, the construction being such that assembly, repair and replacement are greatly facilitated.

Still further objects, the uses, advantages and functions of the invention and the preferred form illustrated will be or should become readily appreciated after perusing the following description and claims, and after viewing the drawings, in which:

Fig. 1 is a side elevational view of the inner side of an end loop of a gas fired radiator constructed in accordance with the invention, and

Fig. 2 is a transverse sectional view of several interior loops of a multiple loop gas fired radiator looking downward toward the combustion chamber.

The expressions "radiator loop" and "loop", as used herein, are intended to mean a radiator unit which in itself, when

assembled with other units of the same or similar character, may form a complete radiator, and these expressions are further intended to include radiator units, that is, loops having one, two, three, or more columns. In the drawing the end loop in Fig. 1 is generally designated 2, and the intermediate loops in Fig. 2 are designated 3, each loop being an individual casting but adapted to be assembled with other loops to provide a radiator with any desired number of loops. It should be understood at the outset, however, that all of the loops of the assembled radiator need not be provided with combustion chamber portions, for some of the loops may be of the usual and ordinary type while the remainder are of the gas or fuel fired type, as illustrated, although my invention is useful only in connection with those loops against or past which the products of combustion contact and flow.

In the illustrated embodiment of the invention each loop is provided with hollow top and bottom headers 5 and 6, respectively, which are integrally joined to and connected by six columns designated 7. The end loops 2 may be made substantially identical with one another except for such details as the gas and water filling connections etc., as will be understood, and a description of one should suffice. Each end loop on its interior side, that is, its side adapted to be adjacent another loop, and each intermediate loop on both sides will, in the embodiment of the invention illustrated, be equipped with top and bottom header connection bosses 8 and 9 into which connecting nipples fit to join the several loops together in water and steam tight relation to permit circulation of water and steam from one loop to another in the radiator.

One or both end loops may be provided with a cored out area 11 providing a combustion chamber, that is, a portion of the combustion chamber, beneath the bottom header. The outer side of this combustion chamber portion into which a portion of the gas or other burner may project is preferably closed by an end plate 12 which may be secured in position in any suitable manner and may aid in supporting the burner in position. The intermediate loops 3 are each likewise provided with six columns 13 joining the top and bottom headers thereof and with combustion chamber portions which, when the several loops are assembled together with the chambered end loop or loops, together form a complete combustion chamber within which the burner is located.

The end loops on one side and the intermediate loops on both sides about the margins of the combustion chamber may be provided with a rib 14. These ribs do not extend entirely across the bottom headers

over the combustion chamber portions, but terminate a sufficient distance to one side or the other of the connection bosses 9 to permit the gases and other products of combustion to flow upwardly between the ends and the bosses. A construction similar to this is illustrated in Daily Patent No. 1,681,173, dated August 21, 1928, entitled Radiator, and assigned to the assignee of this application. These laterally projecting ribs on opposed sides of adjacent loops are arranged to abut against one another at their external edges in any suitable manner to more or less completely inclose the combustion chamber between the adjacent portions of mating ribs and their transversely extending bottom portions may be cut away to provide proper inlets for the admission of air to support combustion in the combustion chamber. I prefer to provide air inlet openings 15 through the bottoms of the shells of the loops from the combustion chamber portions after the manner described and claimed in the said Daily application. The several loops are provided with registering apertures 16 through which tie rods or bolts pass and secure the several loops together.

If the radiator be constructed as thus far described, the hot gases and other products of combustion will be free to pass upwardly in contact with practically the entire radiating surface of the columns and top header, and very little of such surface area will be useful for condensation with the result that the heating efficiency of the radiator is very low. This constitutes a serious problem which I have found may be solved if the gases and other products of combustion rising from the combustion chamber are confined to a very small portion of the total condensation area of the column or columns and top header. This is accomplished in the form of the invention illustrated by providing on one side of each end loop and on both sides of each intermediate loop a pair of ribs 17 and 18, respectively, adapted to mate with and abut against the corresponding opposed ribs of an adjacent loop. These ribs, what I may term the flue ribs, at their lower ends are spaced from and above the rib 14 to provide air vents indicated by the arrows which may aid the draft upward through the flue and tend to draw cold air in toward the bottoms of the columns. From a point spaced from the ribs 14 the ribs 17 extend upwardly in spaced relation to the connection bosses 9 and in spaced relation to one another along the sides of adjacent columns to places adjacent the tops of the columns. Thus gases and other products of combustion rising from the combustion chamber pass up through a central flue, are confined thereto and are restricted to contact with a very small portion 130

of the condensation area of the columns and the top header.

An arrangement of this character serves not only to give a maximum condensation area, but it induces a circulation of air inwardly from the sides of the radiator toward the flue and gives a maximum cold air contact with the condensation or heat transfer surfaces. The inward and upward flow of cold air also seems to enhance the necessary draft upward through the flue so that the proper draft and flow of air to the combustion chamber through the vents 15 is maintained.

It is believed that the advantages, uses and functions of my invention as well as the simplicity thereof will have been appreciated from the foregoing and it will also be appreciated that the invention is susceptible of many other embodiments and embodiment in other types of radiator loop construction bearing little, if any, resemblance to those illustrated. I do not, therefore, desire to be limited except by the spirit of the invention and the scope of the appended claims.

I claim:

1. In a radiator of the character described, a loop comprising columns, a header connecting said columns, means providing a portion of a combustion chamber below said header, a laterally projecting rib secured to said loop on one side thereof and bounding the sides and the bottom of the combustion chamber, and an inwardly and upwardly directing rib secured to said loop and having a portion spaced above the first said rib.

2. In a radiator of the character described, a loop comprising columns, a header connecting said columns, means providing a portion of a combustion chamber below said header, a laterally projecting rib on one side of said loop and extending downwardly along said means from a place adjacent the top of the combustion chamber on each side and across the bottom thereof, and a second laterally projecting rib on the same side of the loop, said second rib having a portion spaced from and above the top of one end portion of the first said rib and extending generally diagonally upward and inward toward the center line of the loop.

3. In a radiator of the character described, a loop comprising columns, a header connecting said columns, means providing a portion of a combustion chamber below said header, a laterally projecting rib on one side of said loop and extending downwardly along said means from a place adjacent the top of the combustion chamber on each side and across the bottom thereof, a second laterally projecting rib on the same side of the loop, said second rib having a portion spaced from and above the top of one end portion of the first said rib and extending generally

diagonally upward and inward toward the center line of the loop and a third laterally projecting rib on the same side of the loop, said third rib having a portion spaced from and above the top of a portion of the other end of the first said rib and extending generally diagonally upward and inward toward the center line of the loop, said second and third ribs being spaced apart at their upper inner ends.

In witness of the foregoing I affix my signature.

GLEN C. CARNAHAN.
